DESIGN FOR A BLOW FAN

Ralph Pryne, Los Angeles, Calif.

Application May 7, 1945, Serial No. 119,434

Term of patent 14 years

(Cl D26—7)

To all whom it may concern:

Be it known that I, Ralph Pryne, a citizen of the United States, and resident of Los Angeles, county of Los Angeles, State of California, have invented a new, original, and ornamental Design for Blow Fan, of which the following is a specification, reference being had to the accompanying drawings, forming part thereof.

Fig. 1 is a plan view of a blow fan showing my new design,

Fig. 2 is a side elevational view of the blow fan shown in Fig. 1.

Fig. 3 is a plan view of the other side of the blow fan shown in Fig. 1, and

Fig. 4 is a sectional view of a detail taken on the line 4—4 of Fig. 1.

I claim:

The ornamental design for a blow fan, as shown.

RALPH PRYNE.
